UNITED STATES PATENT OFFICE.

GEORGE FRANCIS ROWE, OF OTTAWA, ONTARIO, CANADA.

TOY.

Application filed November 10, 1921. Serial No. 514,375.

To all whom it may concern:

Be it known that I, GEORGE FRANCIS Rowe, a subject of the King of Great Britain, and resident of the city of Ottawa, 5 in the Province of Ontario and Dominion of Canada, have invented certain new and useful Improvements in Toys, of which the following is a specification.

This invention relates to improvements in 10 toys, and more particularly to improvements in that class of toy comprising rocking horses and the like.

The objects of the invention are to provide an inexpensive and practical toy, which 15 will, not only be a source of amusement, but will also constitute means whereby healthy bodily exercise may be obtained without any risk. In other words, an instructive playing that will provide health and enjoyment 20 for children at a minimum expense.

A further object is to provide a toy of this character that will produce in action the several movements of a horse cantering, thereby imparting to the rider unconsciously a preliminary 25 knowledge of how to ride.

With these and other objects in view, hereinafter more fully referred to, the invention consists essentially of a saddled toy horse with a swivel-mounted fore part provided 30 with separate front wheels for the fore legs and having the hind legs mounted on a crank shaft carried by a pair of hind or rear wheels, spring actuated supporting means for said toy, and means thereon for resting 35 the feet of the rider, and means for guiding and turning the fore part as required.

Referring to the drawings, in which like numerals of reference indicate corresponding parts in each figure, and in which:

40 Figure 1 is a side elevation partly in section.

Figure 2 is a rear end view.

Figure 3 is a plan view, showing means of attaching the rear wheels to the body of the 45 toy.

Figure 4 is a fragmentary front view.

Figure 5 is an enlarged fragmentary plan view of the swivel turning means for the fore-part.

50 Figure 6 is a side elevation of Figure 5.

Figure 7 is a fragmentary elevation of an alternative form of the supporting means.

Figure 8 is a plan view of the same.

In the drawings:

55 A is a toy horse comprising a body portion 10 including the fore part 11 and the

hind part 12, provided with fixedly secured fore legs 13 and pivotally secured hind legs 14. The fore part 11 is securely mounted to turn horizontally in any required direction and, to this end, is provided with swivel plates 15 and 16 fixedly secured within the top and bottom, respectively, of the body portion adjacent to the neck. These plates are formed with circular extensions centrally 60 apertured at 17 and adapted to fit snugly in operative contact with each end of a vertically extending tubular extension 17^a on the fore part 11, and to be pivotally held in engagement therewith by means of a securing pin extending through said plates and through said tubular extension 17^a.

18 and 19 are the front and rear wheels in the form of my invention as illustrated, on the former of which are pivotally mounted 70 the fore legs 13, the pivotally mounted hind legs 14 being loosely mounted on a crank 20 of a shaft 21 having keyed thereto the hind wheels 19.

22 is a body supporting member bifurcated at its lower end to be loosely secured on the shaft 21, and formed with a flat portion 22' at the other end adapted to be secured on the underneath portion of the body 10 at 23.

80 As shown in Figure 7, an alternative form of this support includes the member 24 provided with a spiral spring 25, which may be used if desired to give more resiliency.

85 26 is a suitable saddle or seat, and 27 are 90 foot rests carried by the fore legs 13 adapted for the feet of the rider to rest upon. 28 is a bridle with guiding reins 29 adapted in combination with the rider's feet on the rests 27 to operate the swivel-mounted fore part 95 11 to turn said fore part in any required direction.

95 From the foregoing, it will be readily seen that, on the rider getting into the saddle or seat 26, and the toy being set in the position 100 as shown in Figure 1, with the crank of the shaft 21 extending upwardly, his weight will tend, through the pivotally mounted hind legs, to press the shaft downwardly and forwardly, causing the hind wheels to rotate 105 and the toy as a whole to move.

Where it is preferred not to set the crank-shaft in this position, the toy can be also automatically started by the rider getting on it at the top of an incline, but the simplest 110 way, and one that applicant generally uses under ordinary conditions, is for the rider to

get on the horse, and then start the horse by giving it a slight forward push, when it will travel afterwards more satisfactory and with great pleasure to the rider, imparting at the same time an up-and-down movement corresponding to a considerable extent to the natural movements of a horse.

To further intensify the realization of riding a live horse, the rider of my toy with 10 the feet pressed on the fore rests 27, will bring the knees on each side of the swivel operated fore part 11, and by using the knees in co-operation with the handling of the reins 29, the toy head can be guided or turned in any required direction.

It will, therefore, be seen that the user of my toy will experience in a lesser degree, all the pleasure, benefit and movement associated with horse riding.

As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

30. 1. A toy comprising a horse-shaped body portion having an operatively mounted fore-part with fixedly secured fore legs provided

with a front wheel, pivotally secured hind legs loosely mounted on a crank-shaft keyed to a pair of wheels adapted to form the rear 35 wheels; a spring actuated supporting member mounted on said shaft and engaging said body portion underneath, means on the front legs for supporting the rider's feet, and seating means on the top of the body portion 40 adapted for the rider, and means for guiding the fore-part.

2. A toy comprising a horse shaped body portion having a swivel-mounted fore part provided with a fore wheel and pivotally 45 supported hind legs mounted on a crank-shaft provided with rear wheels, spring supporting means connecting the shaft and the body portion seating means on the top of the body.

3. A toy comprising a horse-shaped body provided with a swivel-jointed fore part having fore legs mounted on a wheel and hind legs mounted on a crank shaft carried by a pair of rear wheels, spring supporting 55 means for the body portion, seating means on said body, and means for resting the feet on the fore part, and rein means for the fore part.

In witness whereof I have hereunto set 60 my hand in the presence of a witness.

GEORGE FRANCIS ROWE.

Witness:

W. T. CUFFE REMI.
